SAFETY LOCKABLE COVER FOR GAS RANGES

Milton Applebaum, New York, N. Y.

Application May 31, 1943, Serial No. 489,233

2 Claims. (Cl. 126—42)

This invention relates to a simplified safety control device for the burner valves of gas cooking stoves or gas ranges having their front and top surfaces lying in right-angular planes and having handles movable parallel with one of said planes.

An object of this invention is to provide mechanism installable solely in an improved top cover designed for covering both the top burners and the valve handles when the burners are not in use, the said mechanism comprising cam elements adapted for automatically partly closing one or more of the valves that may be open.

Another object of this invention is to provide an elongated top cover for covering the top burners, which is long enough to overlap the burner valves and to provide an overhanging plate at the front portion of the cover and in right-angular relation with the cover, for concealing the burner valves and prevent any burner valve from being open when the cover is in full closed position.

Another object of this invention is to provide a control bar attached to the cover and being slideable relative to the under side of the cover, the cover being hinged at the rear of the gas stove to permit the cover and control bar to be swung upwardly as a unit out of the way of both the valves and burners and to secure a substantially vertical reciprocating movement of the control bar when the bar comes in contact with a valve handle in open position.

Another object of this invention is to provide ears projecting rearwardly of the control bar and engageable with the valve stems, and to provide means for engaging the slideable control bar for manually moving the bar horizontally relative to the cover after it has been swung down to closed position and thereby complete the closing of the valves and simultaneously cause interlocking engagement of the cover with the valve stems.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a perspective view of a gas range having a cover in which my control mechanism is incorporated, the cover being in open position.

Figure 2 is a view similar to Figure 1, but showing the cover in closed position.

Figure 3 is a fragmentary cross-sectional view, the section being taken as on line 3—3 in Figure 2, and showing two valve handles in open position.

Figure 4 is a fragmentary cross-sectional view, similar to Figure 3, and shows a valve handle in partly closed position.

Figure 5 is a fragmentary cross-sectional view, the section being taken as on line 5—5 in Figure 3.

Figure 6 is a fragmentary cross-sectional view, similar to Figures 3 and 4, and shows a valve handle in closed position.

In the illustrated embodiment of the invention, the numeral 10 indicates a gas range or gas cooking stove of the cabinet type, comprising burners 11 and burner control valves 12.

The gas range 10 is also provided with a cover 13 which is hinged on a pin 14 at the rear of the gas range. The valves 12 have operating handles 15 by means of which the valve stems are given ninety degree movements.

For the purposes of this invention the cover 13 is made long enough to overlap the valves 12. At the front portion of the cover there has been provided an overhanging plate 16 which extends downwardly sufficiently to conceal the valve handles 15.

Figure 3 is a cross-sectional view, the section being taken as on line 3—3 in Figure 1, and shows a control bar or locking bar 18 in fragmentary form. The control bar 18 is slideably mounted in concealed relation, rearward of the overhanging front plate 16. Brackets 19 fixed to the lower surface of the cover 13 provide bearings at both ends of the control bar 18 whereby the control bar 18 is attached to the cover 13.

The control bar is positioned in vertically superposed relation directly over the valve handles 15 when the cover 13 is in lowered position over the gas range 10. The control bar has openings 20, one for each valve handle. One surface portion 21 of each opening 20 is cam shaped and positioned so as to contact a valve handle when the handle is horizontally positioned, that is, when the valve is in open position.

When the user swings the cover downwardly, the cam surface 21 contacts the horizontally positioned valve handle 15 and this contacting relation remains during the continuing downward movement of the cover. At the lowest downward position of the cover, the valve handle 15 is not at its desired ninety degree position because of

the diminished leverage at the said lowest position.

For the purpose of completing the movement of the valve handle to full ninety degree valve closing position, the user applies a sideways pressure against button 22 positioned in front of the plate 16 and having a stem 23 connected to the control bar 18. The stem 23 is slidably mounted in an elongated slot 24 in the plate 16, the slot being sufficiently long to permit the control bar to move horizontally and to move the valve handle 15 to full vertical closing position.

A latch bolt 25 is pivotally mounted on a pin 26 passing through a forked end 27 of the control bar 18. A stop 28 is secured to the cover 13 and serves for engagement with an angular tooth 30 on the latch bolt 25. Upon completion of the horizontal movement of the control bar 18, a spring 31 secured to the plate 16 presses the latch bolt 25 into engagement with the stop 28. The control bar is then held in fixed position horizontally and the valve handles are then held in fully closed position.

It is to be noted that ears 32, integral with the control bar 18, are provided rearward of the control bar. The ears project rearwardly of the control bar a distance sufficient to permit the ears to clear the valve handles 15 and to move under the valve stems 33. In this position, the ears are between the valve handles and the casing of the gas range. The ears have upper horizontal surfaces which, when in engagement with the undersurfaces of the valve stems, lock the cover 13 to the gas range 10 when the cover is in closed position and the horizontal movement of the control bar is completed.

It will thus be noted that there has been provided a unitary cover and built-in mechanism for closing the valves on gas ranges, and that this unitary device is adapted for installation as an attachment to gas ranges already built.

As a safety feature against the manipulation of the mechanism by children, there has been incorporated two movements in addition to the usual vertical swinging movement of the cover. It is first necessary to use the right hand to release the latch bolt 25 and to use the left hand to grasp the button 22 and move the control bar 18 to the left to release the valve stems from the cover before it is possible to move the cover upwardly, away from the gas range. This two hand operational requirement provides a safety feature against the turning on of the gas by children and prevents accidents.

From the above it will be seen that the main gist of this invention is to provide a unitary cover and burner control attachment which may be attached as a unit on new or on existing gas stoves and supported in its entirety externally of the stoves.

Devices of the nature herein described have been made heretofore by redesigning the gas stoves proper. Also by arranging the valve handles so that their movements are not parallel to either the top or front face of the gas stove.

The demand of gas users is for gas stoves having handles, the movements of which are parallel to the front face or parallel to the top face of the

gas stove, so that their movements are solely between full vertical and full horizontal positions and so that mistakes can not be made in their operation, that is, movements wherein the handles are either perpendicular or parallel to one of these surfaces, as distinguished from in-between angular positions.

In accordance with the patent statutes I have described and illustrated the preferred embodiments of my invention, but it will be understood that various changes and modifications can be made therein without departing from the spirit of the invention as defined by the appended claims.

I claim:

1. In a gas stove, the combination with a plurality of burners having manually operable valves controlling the delivery of fuel to the individual burners, valve handles movable through a ninety degree arc and designed to open said valves when in horizontal position and to close said valves when in vertical position, a cover and burner control attachment unit, said unit being in its entirety pivotally mounted at the rear of said gas stove and being movable between open and closed positions relative to said burners, a locking bar attached to and being horizontally slidably mounted in said cover and comprising cam means positioned in spaced-apart relation and in alignment with said valve handles, said bar having openings permitting surface portions on said cams to engage with said handles to cause movement of said handles downwardly, said bar having additional means which engage portions of the valves when the locking bar is horizontally slid on the cover after the cover is in closed position, said cover and burner control attachment being actuated externally of said stove, and latch means engageable within said cover to retain said cam means in alignment with said valve handles and to retain said additional means in engagement with said valve portions to thereby lock said bar and cover to said stove.

2. In a gas stove, the combination with a plurality of burners having manually operable valves and valve stems and valve handles controlling the delivery of fuel to the individual burners, said handles being movable through an arc and designed to open said valves when in one position and to close said valves when in another position, a cover and burner control attachment unit, said unit being in its entirety pivotally mounted at the rear of said gas stove and being movable between open and closed positions relative to said burners, a locking bar attached to and being slidably mounted in said cover and comprising cam means and ears adapted to be brought into alignment with said valve handles, said bar having openings permitting surface portions on said cams to engage with said handles to cause movement of said handles downwardly, said cover and burner control attachment being actuated externally of said stove, and latch means engageable within said cover to retain said cam means in alignment with said valve handles and said ears in engagement with said valve stems upon horizontal sliding movement of said bar to thereby lock said bar and cover to said stove.

MILTON APPLEBAUM.
